(57) **CLAIM**

We claim the ornamental design for a faucet, as shown and described.

DESCRIPTION

FIG. 1 is a perspective view of a faucet of the claimed design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The broken lines formed by equal length dashes indicate portions of the faucet that form no part of the claimed design. The broken lines formed by dash-dot lines indicate the bounds of the claim and form no part of the claimed design.

1 Claim, 5 Drawing Sheets
